UNITED STATES PATENT OFFICE.

ROBERT VAN BENTHUYSEN, OF NEWARK, NEW JERSEY.

COMBINED HYDROMETER AND SYRINGE.

SPECIFICATION forming part of Letters Patent No. 756,546, dated April 5, 1904.

Application filed June 29, 1903. Serial No. 163,509. (No model.)

To all whom it may concern:

Be it known that I, ROBERT VAN BENTHUYSEN, a citizen of the United States, and a resident of Newark, in the county of Essex and State of New Jersey, have invented a new and Improved Combined Hydrometer and Syringe, of which the following is a full, clear, and exact description.

The purpose of my invention is to prevent hydrometer-tubes from touching the side walls of syringe-barrels and to provide means whereby to prevent rotary motion of the hydrometer in said barrels.

A further purpose of the invention is to construct the reading or scale section of a hydrometer-tube that it will be polygonal in cross-section, having a reading upon one face, for example, indicating density, upon another face degrees Baumé, and upon the third face a reading setting forth a required percentage of liquid or fluid to bring the solution tested to proper density, which reading is that illustrated.

Another purpose of the invention is to provide wings at the bottom or lower portion of the hydrometer-tube, which by engagement with the contents of the syringe-tube will prevent the hydrometer-tube from having rotary motion while in use, thereby further facilitating the reading of the scale-section of the hydrometer.

A further purpose of the invention is, by producing an apertured obstruction in the syringe-tube, to obtain a valve-action when the hydrometer rises so high that the upper bulb or swell in the lower portion of the hydrometer-tube is brought into engagement with the aforesaid apertured obstruction, at which time the said liquid or fluid seeking entrance at the inlet of the syringe-tube will be cut off from the compression-bulb of the syringe-tube, preserving the said bulb against detrimental action from such source.

The invention consists in the novel construction and combination of the several parts, as will be hereinafter fully set forth, and pointed out in the claims.

Reference is to be had to the accompanying drawings, forming a part of this specification,

in which similar characters of reference indicate corresponding parts in all the figures.

Figure 1 is a vertical section through the body portion of the device, the bulb of the syringe-tube being partially in side elevation and partially broken away. Fig. 2 is a transverse section taken practically on the line 2 2 of Fig. 1, being drawn on a larger scale; and Fig. 3 is a similar section taken substantially on the line 3 3 of Fig. 1, being drawn on the same scale as the parts shown in Fig. 2.

A represents a syringe-tube of any desired length and of any desired diameter. The said syringe-tube A, which is preferably made of glass, is provided with an upper neck member 10, into which the shank 11 of a rubber compression-bulb B is introduced, said compression-bulb B being of any approved construction. As shown, the said bulb is provided with a central passage 12 in its shank, communicating with the interior of the syringe-tube A.

At the lower end of the syringe-tube A a nozzle 13 is formed continuous with the said tube and of less diameter than the body of the tube. This nozzle is closed at its lower end, except that a central opening 14 is produced in the bottom portion of the nozzle, through which liquid of any description may be drawn up into the syringe-tube by the action of the compression-bulb B. Where the body of the syringe-tube A connects with the nozzle 13, a segmental seat 15 is formed, as is shown in Fig. 1, and preferably about centrally between the ends of the syringe-tube A an exterior annular depression 16 is produced, (shown best in Fig. 1,) thereby forming an inner annular flange 17, dividing the syringe-tube A into an upper compartment a and a lower compartment a', the two compartments being connected by a passage-way a², as is also shown in Fig. 1.

The hydrometer C is located as usual in the lower portion of the syringe-tube A, and in the construction of the hydrometer C an upper tubular scale-section 18 is formed, which scale-section, as is best shown in Fig. 2, is shown as exteriorly triangular in cross-section. Upon one face of this reading or scale

- section 18 of the hydrometer a scale-indicating density is produced, on another face a scale representing degrees Baumé is likewise produced, and on the third face a scale is made which indicates the required percentage of liquid or fluid necessary to bring the solution being tested to the proper density. This reading or scale section 18 of the hydrometer is continuous with and in direct communication with the usual elongated reception-bulb 19, which reception-bulb 19 is connected by a suitable neck 21 with a lower weight-carrying spherical bulb 20, the latter bulb 20 being adapted in the normal position of the hydrometer to rest upon the seat 15.
- It will be observed that the upper scale or reading section 18 of the hydrometer C, when the hydrometer is in its lower or normal position, extends up into the upper compartment 20 or chamber α of the syringe-tube A and that the inwardly-extending annular flange 17, formed in the syringe-tube A, affords the said reading or scale section α of the hydrometer sufficient play for all practical purposes, yet at the same time serves to maintain the said portion of the hydrometer in a vertical or perpendicular position, thus facilitating the reading of any of the scales produced upon the said portion of the hydrometer.
- At opposite sides of the portion 21, between the elongated receptacle 19 and the weight-carrying bulb 20 at the bottom of the hydrometer, wings 22 are formed, and these wings, as is especially shown in Fig. 3, engage with the liquid in the lower compartment α' of the syringe-tube A and serve in action to prevent the hydrometer from having a rotary motion, which motion materially interferes with the accurate and convenient reading of the scales on the reading-section 18 of the hydrometer. Furthermore, it is obvious that in a test when the hydrometer is carried upward by the incoming fluid and the hydrometer reaches such a high point as to bring the elongated reception-bulb 19 in engagement with the inner flange 17 of the syringe-tube or equivalent obstruction the upper bulb will close communication between the two chambers or compartments α and α' and will effectually prevent any excess of fluid entering the syringe-tube by the operation of the compression-bulb B from passing up into the upper chamber or compartment α and being brought into contact with the compression-bulb B to the detriment of the latter.

It will be observed that in the construction of this syringe due consideration has been given to the proper operation of the hydrometer in the syringe-tube, and, furthermore, that

all possibility of any of the fluid reaching parts 60 not desirable to be so reached is effectually obviated.

In Fig. 1 I have shown a reading setting forth the required percentage of liquid or fluid to bring a solution—as, for example, a battery solution—to proper density, such scale reading in opposite directions from "0" to "25," or a greater or a less figure. In reading the scale upward the percentage of acid is indicated. Upon reading the scale downward the percentage of water is indicated. For example, if the reading is "10" in the upper division of the scale it will indicate that ten per cent. of acid is required to bring the solution to normal state, and if the reading is 75 "10" in the lower division of the scale ten per cent. of water should be added to bring the solution to the proper strength.

Having thus described my invention, I claim as new and desire to secure by Letters Patent— 80

1. The herein-described instrument, consisting of a syringe-tube provided with a compression-bulb at its upper end and having a nozzle at its lower end, which nozzle has a bottom opening, the said syringe-tube having 85 an interiorly-reduced diameter between its ends, and a hydrometer adapted to have its lower end normally seated in the said syringe-tube above the nozzle end of the tube, the reading-section of the hydrometer being 90 adapted to pass through the contracted portion within the syringe-tube, whereby the hydrometer is held in a vertical position and is preserved against undue lateral play to facilitate the reading of the scales on the hydrometer, as and for the purpose described.

2. The herein-described instrument, comprising a syringe having a transparent barrel, a guide within the barrel of the syringe, a hydrometer movable in said barrel, the reading-section of which hydrometer passes loosely within and through the said guide, whereby to substantially center the hydrometer and prevent the reading-section from engaging with the side walls of the barrel, and wings 105 adjacent to the bulb of the hydrometer, extending from opposite sides thereof, which wings serve to prevent the hydrometer from being given rotary movement in the said barrel by the action of liquid contained therein, 110 as specified.

In testimony whereof I have signed my name to this specification in the presence of two subscribing witnesses.

ROBERT VAN BENTHUYSEN.
